UNITED STATES PATENT OFFICE.

ARTHUR LEE, OF HERSCHER, ILLINOIS.

PORTABLE POWER TRANSMISSION.

1,253,396.

Specification of Letters Patent. Patented Jan. 15, 1918.

Application filed June 17, 1915. Serial No. 34,626.

To all whom it may concern:

Be it known that I, ARTHUR LEE, a citizen of the United States, residing at Herscher, in the county of Kankakee and State 5 of Illinois, have invented certain new and useful Improvements in a Portable Power Transmission, of which the following is a description.

My invention belongs to that general class 10 of devices for transmitting power, and relates particularly to a portable device for efficiently and conveniently transmitting power from a suitable source of energy to one or more desired machines. The invention herein described is in the nature of an improvement on that shown in my United States Letters Patent No. 1,089,485, dated March 10, 1914. The device is particularly adapted for farm use, as the source of 15 power, as for example a gas engine, and may be transported from place to place to operate the desired machinery, such as churning, washing machines, pumps, grinders, shellers and similar tools or appliances.

The invention has particularly among its 20 objects the production of an improved portable device of the kind described that is extremely simple, convenient, efficient and satisfactory, and that is applicable for practically any use to which it may be put. The present construction has the advantage of being adjustable for slight variations whereby the same may be used for driving almost any machine regardless of where the machine is located, and driving it in a most 25 efficient manner.

To this end my invention consists in the novel construction, arrangement and combination of parts herein shown and described, and more particularly pointed out in the claims.

In the drawings, wherein like reference characters indicate like or corresponding parts,

Figure 1 is a side elevation of the truck and transmission elements carried thereby;

Fig. 2 is a rear elevation of the same;

Fig. 3 is a top elevation of a portion of the same, the engine removed;

Fig. 4 is a sectional view taken substantially on line 4, 4 of Fig. 3;

Fig. 5 is a sectional view taken substantially on line 5, 5 of Fig. 1;

Fig. 6 is a view in elevation of the auxiliary apparatus arranged to cooperate with

the main transmission mechanism shown in Fig. 1;

Fig. 7 is a top plan view of the same, and

Fig. 8 is a sectional view taken substantially on line 8, 8 of Fig. 3. 60

Referring to the drawings, my apparatus consists preferably of a truck frame consisting of the parts 1 and 2 suitably carried by the wheels 3, or their equivalents for the purpose. Mounted on the truck frame is an 65 upright frame, consisting of the brace and upright members 4, 5 and 6 respectively. Suitably carried by the upright frame is a shaft 7, and adjustably carried on the shaft, or in an equivalent manner, is an adjustable 70 or swinging frame 8, which carries a shaft 9 arranged adjacent the outer end. The frame 8 is very similar to the frame shown in my patent referred to. Arranged on each side 8 of the frame is what might be 75 termed a gear or toothed member 10, the same being secured to the arm by bolts 12, or their equivalents, passing through the spokes 11. Suitably carried by the upright 80 4 at each side of the machine is a gear 14, arranged to mesh with the teeth on the member 10. The gear 14 on one side is connected through the shaft 15 with the worm wheel 16, arranged to mesh with a worm gear 17 carried by bracket 18. The worm 85 gear 17 is arranged to be driven or controlled by a shaft 19, preferably provided with a crank end 20. As is obvious, as the crank 20 is turned in one direction or the other, the wheel 10 at each side of the machine is turned, through the shaft 15 and gears 14. At the same time, owing to the worm gear construction, the worm gear locks the gears 10, and consequently the arms 90 8 of the adjustable frame, against movement. This avoids the necessity of additional fastening or locking members, and the adjustable frame may be instantly changed or varied for extremely slight adjustment in but a moment's time. 95

I have shown a pulley 21 on shaft 7, and this through belt 22, or its equivalent, drives pulley 23 on shaft 9. Shaft 7 is driven by belt 24, or its equivalent, passing over the pulley 25, operatively connected with the gas 105 engine 26, or its equivalent. I have shown a tight and loose pulley 27 and 28 on shaft 7, and a belt shifter 29, so that shaft 7 may be stopped without shutting down the engine. 110

To avoid the necessity of adjusting shaft 7 and the arms 8 to loosen or tighten belt 24, I mount the engine 26 on an adjustable frame, said frame being adjustable relative 5 to the upright frame on the truck. This frame, as is most clearly shown in Figs. 3, 4 and 8, consists of the sliding frame parts 31 and 32, projecting over the side frame parts 1 of the truck, and parts 33 and 36 arranged 10 below the parts 1, members 34 being arranged therebetween, as shown in the drawings. The parts are secured together by bolts 37, this forming substantially a sliding frame. The position of the sliding 15 frame is controlled by the bolts 42, which also lock the frame in the desired position relative to the upright frame, so that the belt 24 may be maintained at the desired tension and prevent strain on the upright 20 frame. I have shown braces 38 secured by bolts 39 to the parts 34. When the cross bar 32 is shifted and the bolts 37 extended through the desired holes 40 the braces may then be secured to the cross bars 31 and 32 25 by passing the bolts 39 through the bolt holes 41. These last mentioned bolt holes are also convenient for securing the engine in place.

It is often necessary or desirable to leave 30 the truck outside of the building and yet drive a machine within the building, as for example, a washing machine, churn, or the like, which may be in the kitchen or in the milk house on a farm. By making the arms 35 8 adjustable to any point this may be very simply done. I have shown in Figs. 6 and 7 the coöperating driving element, which is connected with one of the shafts on the truck, as for example, shaft 9, as that shaft 40 45 may be brought to aline with the transmitting shaft arranged within the house and coupled directly thereto. It is also possible to bring the shaft to exactly the right position above the window sill, even though the various window sills differ in height from the ground.

Referring particularly to Figs. 6 and 7 mentioned, 46 is the shaft, which is arranged to be connected directly to shaft 9, but may 50 be provided with a pulley 47 in addition, if so desired. Shaft 46 extends through and is carried by a bearing 48, formed with supporting brackets 49 for securing the same in place. I have shown the bearing and brackets secured to a board 50, which has hinged thereto a board 51, 52 being hinges. This construction, consisting of the two boards 50 and 51, may be inserted under the window frame or sash and the sash then brought 55 60 down on the same, securely locking the device in place. This rigidly supports shaft 46. Preferably pivotally or adjustably carried by shaft 46 is an auxiliary adjustable frame 53, which carries a shaft 54. The two 65 shafts are connected by a belt 57 running

over pulley 58 and arranged to coöperate with the tight and loose pulleys 55 and 56. The belt shifter 59 is also shown. To support the auxiliary frame 53 I secure an adjustable leg 60 adjacent the free end of the 70 frame. This leg is secured in place by a bolt 63. I have shown in Fig. 7 serrated plates 61 and 62, secured respectively to the frame and leg so as to give a firm grip and prevent movement of the leg around the bolt 75 63. The leg is also shown with a slot so the auxiliary frame may be adjusted up and down.

In driving a machine within a house or room, the truck being without, the boards 50 80 and 51 are placed under the window sash, frame 53 adjusted as desired, and shaft 54 suitably connected with the churn, washing machine or the like which is to be driven. The truck is brought to the window and 85 crank 20 turned, and through the several gears and adjustable frame 8, shaft 9 is brought to aline with shaft 46, the two being then secured together. The bolts 42, one or the other, or both, may be operated so as 90 to bring the desired tension on the belt 24, and the several belts thrown on to the driving pulleys, thereby driving shaft 54 and the particular machine. The adjustable frame can be brought to exactly the desired 95 adjustment without blocking up the wheels of the truck or digging under the wheels to lower the truck, and likewise the frame 53 may be exactly adjusted so as to bring shaft 54 to the machine to be operated. In this 100 way excess pulleys, belts, and driving shafts are avoided, and adjustments are possible for practically every condition.

Having thus described my invention, it is obvious that various immaterial modifications may be made in the same without departing from the spirit of my invention; hence I do not wish to be understood as limiting myself to the exact construction, arrangement or combination of parts herein 110 shown and described, or uses mentioned.

What I claim as new and desire to secure by Letters Patent is:—

1. In a device of the kind described and in combination, an upright frame, an adjustable frame carried thereby, a shaft carried by said adjustable frame adjacent the end thereof, and means for moving said adjustable frame about its support, and maintaining the same in a desired adjustment, comprising a toothed member secured to said frame, a gear in mesh therewith, a worm wheel connected with said gear, and a worm gear for driving said worm wheel. 115

2. In a device of the kind described and in combination, an upright frame, an adjustable frame pivotally carried thereby, a shaft carried by said adjustable frame adjacent the end thereof, and means for moving said adjustable frame about its support and main- 130

taining the same in a desired adjustment, comprising a gear secured to each side of said frame, a gear for each of said first mentioned gears, said last mentioned gears carried by said upright frame and suitably secured together, a worm wheel connected with one of said last mentioned gears, and a worm gear in mesh with said worm wheel, and means for driving said worm gear as desired.

10 3. In a device of the kind described and in combination, an upright frame, an adjustable frame pivotally carried thereby, a shaft carried by said adjustable frame adjacent the end thereof, and means for moving said 15 adjustable frame about its support and maintaining the same in a desired adjustment, comprising a gear secured to each side of said frame, with their centers at the pivotal connection of the two frames, a gear for 20 each of said first mentioned gears, said last mentioned gears carried by said upright frame and suitably secured together, a worm wheel connected with one of said last mentioned gears, and a worm gear in mesh with 25 said worm wheel, and means for driving said worm gear in either direction, as desired.

4. In a device of the kind described and in combination, a suitable truck frame, an 30 upright frame carried thereby, an adjustable frame carried by said upright frame adjacent the upper end thereof, means for moving said adjustable frame and maintaining the same in a desired adjustment, comprising gear parts secured to said 35 adjustable frame, one on each side thereof, coöperating gears carried by said upright frame and in gear with the gear parts secured to said adjustable frame, and a worm wheel 40 and worm gear operatively connected with said coöperating gears.

5. In a device of the kind described and in combination, a suitable truck frame, an upright frame carried thereby, an adjustable 45 frame pivotally carried by said upright frame adjacent the upper end thereof, means for moving said adjustable frame and maintaining the same in a desired adjustment, comprising gear parts secured to said ad-

justable frame, one on each side thereof, co- 50 operating gears carried by said upright frame, and in gear with the gear parts secured to said adjustable frame, a worm wheel and gear operatively connected with said coöperating gears, a shaft carried by 55 said adjustable frame, a second shaft arranged to be operatively connected with said first mentioned shaft, an adjustable auxiliary frame extending from said second shaft, and provided with a shaft adjacent the free 60 end thereof, means for adjustably securing the end of said auxiliary adjustable frame, means for driving said first mentioned shaft, and means for operatively connecting the same with said other shafts. 65

6. In a device of the kind described and in combination, a suitable truck frame provided with an adjustable frame carried thereby, having a shaft arranged adjacent the free end thereof, a second shaft arranged 70 to connect with said first mentioned shaft, a support for said second shaft, an auxiliary frame adjustably carried by said second shaft, and provided with a shaft at its free end, and means for adjustably supporting 75 said auxiliary frame.

7. In a device of the kind described and in combination, a suitable truck frame, an upright frame rigidly carried thereby, an adjustable frame pivotally carried by said 80 upright frame adjacent the upper end thereof, means for maintaining said adjustable frame in the desired adjustment, shafts carried by said frames, means for driving said shafts including a source of power, and 85 means arranged on said truck frame for adjustably carrying said source of power, and maintaining the same in the desired position relative to the shaft carried by said upright frame. 90

In testimony whereof, I have hereunto signed my name in the presence of two subscribing witnesses.

ARTHUR LEE.
